(57) **CLAIM**

The ornamental design for a pulverizing attachment as shown and described.

DESCRIPTION

FIG. 1 is a front top perspective view of a second variant of a pulverizing attachment with jaws in a first, closed position; FIG. 2 is a rear bottom perspective view of the pulverizing attachment of FIG. 1;

FIG. 3 is a right side view of the pulverizing attachment of FIG. 1;

FIG. 4 is a left side view of the pulverizing attachment of FIG. 1;

FIG. 5 is a front view of the pulverizing attachment of FIG. 1;

FIG. 6 is a rear view of the pulverizing attachment of FIG. 1;

FIG. 7 is a top view of the pulverizing attachment of FIG. 1;

FIG. 8 is a bottom view of the pulverizing attachment of FIG. 1; and,

FIG. 9 is a front bottom perspective view of the pulverizing attachment of FIG. 1, showing the jaws in a second, open, position.

The broken lines shown in the drawings are for illustrative purposes only and form no part of the claimed design.

1 Claim, 9 Drawing Sheets
